(57) **CLAIM**

The ornamental design for a coffee machine with tamp chute, as shown and described.

DESCRIPTION

FIG. 1 is front perspective view of a coffee machine with tamp chute;

FIG. 2 is a back perspective view of the design shown in FIG. 1;

FIG. 3 is a bottom perspective view of the design shown in FIG. 1;

FIG. 4 is a front view of the design shown in FIG. 1;

FIG. 5 is a back view of the design shown in FIG. 1;

FIG. 6 is a right side view of the design shown in FIG. 1;

FIG. 7 is a left side view of the design shown in FIG. 1;

FIG. 8 is a top view of the design shown in FIG. 1; and,

FIG. 9 is a bottom view of the design shown in FIG. 1;

Portions illustrated in broken lines form no part of the claimed design.

1 Claim, 9 Drawing Sheets
